CAN TOP PIERCING TOOL FOR OPENING
AND VENTING IN ONE OPERATIONRalph Robinson, Wauwatosa, Wis., assignor to
Milwaukee Stamping Company, West Allis,
Wis., a corporation of Wisconsin

Application November 19, 1949, Serial No. 128,376

8 Claims. (Cl. 30—6.1)

1

This invention relates to a can top piercing tool for opening and venting in one operation.

It is a primary object of the invention to provide a can opener of the top piercing type which, in one operation, will pierce the can top to provide the usual opening and, in the same operation, will pierce the top at a point remote from the dispensing opening to provide a vent.

It is a further object of the invention to provide a tool in which a vent producing portion of the tool is used to receive the pressure of the operator's thumb to facilitate the manipulation of the tool and increase the pressure which may be exerted therewith.

A still further object of the invention is to provide a simple, one-piece tool in which can piercing members for achieving the foregoing results are unitarily embodied.

In the drawings:

Fig. 1 is a view in side elevation of a tool embodying the invention.

Fig. 2 is a plan view of the tool shown in Fig. 1.

Fig. 3 is a detail view taken in section on the line 3—3 of Fig. 2.

Fig. 4 is a view in perspective showing the tool as it appears when in use.

Fig. 5 is a plan view of a can top which has been opened through the use of the tool, the view showing the relative positions of the punctures made therein.

In the preferred embodiment of the invention as shown in the drawings, a single piece of sheet metal provides a handle portion 7 which may incidentally include a crown cap removing hook at 8. All of the can engaging portions of the tool are located in a head 9 which is desirably wider than the handle. A centrally disposed tongue portion 10 is formed downwardly and has a forwardly directed edge at 11 for engagement beneath the bead 12 of a conventional can 13.

An intermediate portion 14 of head 9 is bifurcated by the slot from which tongue 10 is formed, the portion 14 being connected with the handle by means of legs 15 and 16 lying at opposite sides of such slot. The portion 14 extends downwardly and has sides converging to an apex at 17 positioned to be forced through the top wall 18 of the can to form the dispensing opening 19 therein.

The opening 20 in head 9 which is left by stamping out the prong 14 which forms the dispensing opening, bifurcates an outer prong 21 connected by legs 22 and 23 to the handle. Whereas the prong 14 extends downwardly from the plane of the handle, the prong 21 extends upwardly there-

from. It also has converging sides, which terminate in the forwardly directed apex 24.

In using the tool, the operator's hand encircles the handle 7, and his thumb rests on the prong 21 as shown in Fig. 4. The bead-engaging tongue 10 is hooked beneath the bead 12 of the can to provide a fulcruming connection upon which the tool is oscillated by lifting upwardly on its handle and simultaneously pushing downwardly on prong 21 by exerting the pressure of the thumb thereon.

The first effect of the oscillatory movement is to produce the usual dispensing opening at 19, the prong 14 readily penetrating the can top for this purpose. Continued oscillation of the tool in the same direction will force the prong 24 through the can top to make therein a venting puncture at 25, sufficiently remote from the dispensing opening 19 to assure a satisfactory flow of the contents through the dispensing opening.

Because the upward pressure of the operator's hand on the handle 7 is measurably offset by the downward pressure of the thumb on prong 21 at the opposite side of the fulcrum, there is very little tendency to tilt or otherwise displace the can upon which the tool is operating. For this reason, as well as because of the two-point application of pressure, the tool is exceptionally easy to use.

30 I claim:

1. A can top puncturing tool of the type having fulcruming engagement with a can bead, comprising a lever having a bead-engaging tongue intermediate its ends, a portion of the lever at one side of said tongue constituting a handle, and a portion of the lever at the other side of the tongue being adapted to receive thumb pressure, and a puncturing prong connected with the lever intermediate the tongue and said thumb pressure receiving portion and directed downwardly, said prong and said thumb receiving portion being disposed in intersecting angularly related planes and said handle being disposed in a plane lying between said intersecting planes.

40 2. A tool of the character described comprising a handle and a head wider than the handle, a first piercing prong connected to the head and a second piercing prong connected to the head at opposite sides of the first mentioned piercing prong, the connections of the said second piercing prong comprising bifurcated legs having margins mutually adjacent to the margins of the first piercing prong.

45 3. The device of claim 2 wherein the head is 50 further provided with a bead engaging tongue

connected to a medial portion of the head, said first mentioned prong being provided with bifurcated legs connected to the head at opposite sides of the tongue and having margins mutually adjacent those of the tongue.

4. A tool of the character described comprising a lever having a handle portion and a head, an integral tongue stamped from the lever adjacent the juncture of the handle with the head to leave a first opening in said head, a piercing prong having bifurcated legs connected with the head at opposite sides of said tongue and first opening and curving downwardly therefrom to leave a second opening in said head, and a bifurcated lever portion connected with said head at both sides of said piercing prong and second opening and constituting a thumb-engageable pressure-receiving part of said lever to be thrust downwardly concurrently with the application of upward pressure to said handle and forcing said prong into a can top.

5. The device of claim 4 in which said last mentioned lever portion extends upwardly from said handle and has a terminal piercing apex for cutting its own aperture in the can top remote from the portion of the can top upon which said piercing prong has operated.

6. A tool of the character described comprising a vent piercing prong having a bifurcated base with spaced legs, a second piercing prong for cutting a dispensing opening and disposed between the spaced legs of said base and unitarily connected therewith, and a handle connected with both prongs at said base, the said prongs projecting in opposite directions from the plane of said handle.

7. The device of claim 6 in which the second prong is also bifurcated to provide spaced legs, and the handle is provided with a fulcrum

finger extending angularly from the plane of the handle at the same side thereof at which said second prong projects and provided with a hook for can bead engagement.

8. A tool of the character described comprising a lever composed of a single piece of sheet metal having an elongated handle portion and a head which is wider than the handle portion and joined thereto, a tongue formed downwardly from said lever adjacent the juncture of the handle portion and head and having a forwardly directed hook at its apex, a bifurcated prong having legs connecting it to the lever adjacent the juncture of said head and handle portion and at opposite sides of said tongue, said prong extending obliquely downwardly from the plane of said handle and having a downwardly curving, perforating apex, and a second bifurcated prong having leg portions constituting the widened part of said head and connected with said handle portion externally of the leg portions of the prong first mentioned, said second prong extending upwardly from the plane of the handle and having a forwardly directed apex, said second prong constituting thumb-engageable means for receiving pressure to supplement the upward pressure of an operator's hand on the handle and being adapted to make a venting perforation in a can top punctured by said first prong.

RALPH ROBINSON.
